Attorney.

UNITED STATES PATENT OFFICE

ERNEST J. NOEL, OF IRENTON, OHIO, ASSIGNOR TO LOCOMOTIVE FIREBOX COMPANY,
OF CHICAGO, ILLINOIS, A CORPORATION OF DELAWARE

LOCOMOTIVE BOILER

Application filed September 16, 1929. Serial No. 392,979.

This invention relates to improvements in locomotive boilers and it consists of the matters hereinafter described and more particularly pointed out in the appended claims.

5 In locomotive boilers having a firebox of the combustion type and in which it is desired to install additional water steaming and circulating element as for instance the well known Nicholson thermic siphon, ob-
10 stacles are presented to the forming of an efficient connection for the inlet end of the siphon, due to the relatively low inner throat sheets found in a combustion type of firebox.

15 The main object of the invention is to provide an improved construction in a boiler having such a firebox, which comprises a transverse water wall therein positioned rearwardly from and out of communication
20 with the front water leg, which wall is high enough to receive the inlet end of a siphon without bringing the same into direct contact with the fuel burning upon the grate.

This object of the invention as well as
25 others together with the many advantages thereof, will more fully appear as I proceed with my specification.

In the drawings:—

Fig. 1 is a longitudinal vertical sectional view through a locomotive boiler of the combustion chamber type embodying my invention.

Fig. 2 is a transverse vertical sectional view on an enlarged scale through the same as taken on the line 2—2 of Fig. 1.

Referring now in detail to the locomotive firebox illustrated in the accompanying drawings, the same includes a combined fire and combustion chamber which extends from the back sheet 1 to the flue sheet 2 and from one to the other of the side sheets 3—3. The top of the firebox is formed by a crown sheet 4. 5 indicates the inner front throat and extending from the flue sheet to said inner front throat sheet is the combustion chamber 6. The top of said inner front throat sheet is formed by a portion of the crown sheet, its sides 7 are formed by end parts or continuations of the side sheets and its bottom is formed by a horizontal wall

8 that merges into said sides 7. In this instance the bottom 8 of the combustion chamber extends from the flue sheet to said inner front throat sheet 5 in the manner usual in fireboxes of this kind.

The firebox just described is enclosed by a top sheet 9 and outer side sheets 10—10, an outside front throat sheet 11, and an outside back plate 12 that provides the wrapper for said firebox and connected to said top sheet, outer side sheets and outside throat sheet is the boiler shell 13. The several sheets just above mentioned, together with the various sheets of the firebox define the several water legs of the boiler; namely, the front leg or throat 14, the side legs 14^a and back water leg 15 all closed at the bottom by a mud ring 16. The several coacting sheets are connected together by means of stay bolts 17.

In the inner and outer back sheets, are coacting flanges to provide the fuel door opening 18 and connected to the flue sheet within the shell are the flues 19 through which the products of combustion pass from the interior of the firebox to the smoke box in the manner well known.

A suitable distance to the rear of the front water leg or throat 14 I provide an upright transverse water wall indicated as a whole by the numeral 20 in Fig. 1. This water wall comprises front and rear sheets 21 and 22 which are connected together at the top by a rounded top wall 23 and the bottom ends of said sheets are connected to a cross bar 24 forming a part of the mud ring. The mid portion of the water wall is of a height less than the end portions thereof as shown in Fig. 2 and said end portions have flanges 25 adapted to seat in openings in the side sheets of the firebox and be secured thereto by welding. Thus this water wall which is closed at its top and bottom opens at both ends into the side water legs 14^a of the boiler.

In the bottom of the fire chamber, between the back leg 15 and the water wall 20 is the usual fuel receiving grate as indicated by the dotted line 26 and between the front water leg 13 and said water wall the bottom

of the fire chamber is closed by a wall 27 having an opening and door 28 therein whereby the combustion chamber is accessible for inspection and clean out purposes.

In connection with the structure thus far described I may employ one or more sets of water steaming and circulating elements arranged either fore or aft the water wall or both fore and aft the same and this last mentioned arrangement is best shown in Fig. 1.

The water steaming and circulating elements employed herein constituted what have now become known as the Nicholson thermic siphon and when a plurality of such siphons are employed in both the fire and combustion chambers, those in the combustion chambers are disposed in plane between those in the fire chamber. Such elements may be of the shape or form desired but they all embody the same basic parts; namely, a flat substantially triangular body that opens through the crown sheet and a tubular neck opening into the transverse water wall 20.

25 The siphons in the fire chamber are each indicated as a whole by the numeral 30 and the siphons in the combustion chamber are each indicated as a whole by the numeral 29. In each instance however the siphons each 30 includes a substantially triangularly shaped flat hollow body 31 suitably stay bolted and a tubular neck 32. Each body is open at its top and is flanged for welding in a longitudinally extending slot in the crown sheet 35 in the usual manner.

The neck 32 of each siphon 30 in the fire chamber is engaged and welded in a flexible diaphragm 33 formed in the rear sheet 22 of the water wall 20 while the neck 32 of each 40 siphon in the combustion chamber is engaged in a flexible diaphragm 34 formed in the front sheet of said water wall in a plane below that of the diaphragms in the rear sheet of the water wall. In each sheet of 45 the water wall, in line with the respective diaphragms therein are outwardly convexed dish portion 35 whereby even though the diaphragms extend into said wall, the width thereof in the plane of the inlet necks is in 50 no manner reduced. The opposed sheets of the water wall are stay bolted together to resist internal pressures.

In the operation of the boiler, water enters the water wall from each side water leg 55 of the boiler and then enters the respective inlet necks of the several siphons. The temperature of the water in the siphons is raised whereby a part is generated into steam to increase circulation thereof so that part of 60 said water is discharged above each end of the crown sheet. Thus even though the water line in the boiler falls below normal, the high end of the crown sheet will always 65 be flooded with water.

As the transverse water wall draws water from the bottom end of each side water leg, a fore and aft circulation is produced in said water leg which sweeps the mud ring clean and prevents the accumulation of sediment 70 in the bottom ends of the water legs.

While in describing my invention, I have referred in detail to the form arrangement and construction of the several parts thereof of the same is to be considered merely as 75 illustrative so that I do not wish to be limited thereto except as may be pointed out in the appended claims.

I claim as my invention:—

1. A locomotive boiler embodying therein 80 a firebox having a fire chamber and a combustion chamber, an upright transversely disposed water wall spaced rearwardly from the front throat of the boiler and communicating at its ends with the side water legs 85 only of the boiler and a siphon in each of said chambers and opening at one end through the crown sheet and opening at its other end into said water wall.

2. A locomotive boiler embodying therein 90 a firebox having a fire chamber and a combustion chamber, an upright transversely disposed water wall spaced rearward from the front throat of the boiler and communicating at its ends with the side water legs 95 only of the boiler, a plurality of siphons in the fire chamber and combustion chamber respectively, each siphon including a discharge end opening through the crown sheet and an inlet end opening into said transverse water wall, the inlet necks of the siphon in the combustion chamber opening into said water wall in a plane below that of the necks of the siphons in the fire chamber.

In testimony whereof, I have hereunto set 100 my hand this 9th day of Sept., 1929.

E. J. NOEL.
